UNITED STATES PATENT OFFICE

JOHN A. JOHNSON, OF CRAWFORDSVILLE, INDIANA, ASSIGNOR TO NATIONAL SUPPLY & SERVICE CORPORATION, OF CRAWFORDSVILLE, INDIANA, A CORPORATION

ADJUSTABLE SPARK SCREEN

Application filed October 19, 1932. Serial No. 638,520.

This invention relates to the art of screens adapted to be applied to a flue outlet opening as a means for preventing the escape of sparks from the flue of a size such as would 5 create a fire hazard should the sparks drop upon an inflammable type of roofing. The present invention relates particularly to a structure adapted to be applied to that type of flue outlet wherein the outlet openings are 10 from the sides thereof rather than from the top, a condition found in the usual "Dutch type" of flue construction.

It is my idea to provide a screen structure which will effectively arrest all of the burning 15 particles of soot or trash arising from a fire below and confine them within the screen for a period sufficiently long to permit either the breaking-up of such particles into smaller ones or until the larger particles are 20 completely consumed. In the case of the smaller burning particles escaping from the screen, the screen is so designed that the size of such escaping particles will be such that these smaller particles will be completely consumed or will have gone out by the time they 25 strike the roof below so that there will not be sufficient heat generated on the roof to raise the surrounding roof to the kindling temperature.

Also the structure is so designed that should the screen become filled in with heavy 30 deposit of soot such as may possibly occur in the burning of bituminous coal, particularly in damp weather, the effective flue opening 35 will not be decreased in area thereby and sufficient area is provided through the structure to permit the gases to travel therethrough without a reduction in draft.

It generally occurs that the roof over the 40 top of the flue having side outlets will be irregular in that the vertical edges thereof do not always align with the vertical sides of the flue with the result that some of the masonry will either project beyond the flue 45 wall or be set back from it. It is an object of

my invention to provide a screen structure which may be so adjusted as to take care of such irregularities without the necessity of having to cut the structure in any way and without leaving gaps or other openings between the structure and the flue as would otherwise be the case.

These and other objects and advantages of the invention will become apparent in the following description thereof, with reference 55 being made to the accompanying drawing in which

Fig. 1 is a fragmentary side elevation of a flue to which my invention is applied;

Fig. 2, a fragmentary end elevation of my 60 invention as applied to the flue;

Fig. 3, a top plan view of a screen embodying the invention, and

Fig. 4, a side elevation of a screen diagrammatically showing the various adjustments. 65

Like characters of reference indicate like parts in the several views.

Referring to the drawing, I show a conventional type of flue 10 of the so-called "Dutch type" wherein the two side walls of 70 the flue are carried upwardly and thence brought together at the top to leave end openings, the lower parts of which are each rectangular and the upper parts A-shaped. The upper ends of the side walls are usually 75 joined by the bricks 11 and 12 leaned inwardly to cover the flue.

I form a basket 13 open across the top end, having an outer end wall, two side walls and a bottom, but open entirely across the inner 80 vertical side. In the outer end wall of this basket 13 is formed a horizontally disposed opening formed by slitting the wall horizontally across and vertically at the ends of the horizontal slit and bending inwardly a flap 14 85 thus cut from the wall. The basket may be made of any perforate material such as woven wire or expanded metal such as is commonly employed as lath for plastering. The lower and side edges of the flap 14 as well as the cut 90

edge remaining across the end wall are left with the rough or raw edges of the severed material projecting whereby the entire margin of the opening through the end wall is provided with spikes or projecting teeth which would serve to impale or break-up particles of soot attempting to pass around under the flap 14.

I form a second member generally designated by the numeral 15 out of the perforate material to have its upper portion A-shaped to conform to but to be somewhat larger than the opening under the bricks 11 and 12. In-turned flanges forming side walls are carried from the sloping edges of the member 15 to define a marginal flange therearound and the outer wall between the flanges is carried downwardly to extend well below the base line of the bricks 11 and 12, the outer inwardly extending flange being carried downwardly from the sloping edges of the wall above to extend inwardly from the vertical walls below. Preferably the outer wall of this member 15 is so formed as to have the wires, in the case of the woven material, extend diagonally whereby the width of the wall may be altered by pressing in or pulling out on the vertical edges thereof.

This upper member 15 has its lower portion inserted to within the open end of the basket 13 and is there supported by means of bolts 16 and 17 being carried through openings in the side walls of the basket 13 and openings in the vertically disposed flanges of the member 15, one bolt on each side being sufficient. The width of the flange around the member 15 is appreciably less than the width of the side walls of the basket 13 so that the lower end of the member 15 when inserted within the basket 13 does not completely fill in the top opening of the basket 13 but leaves an appreciable opening between the member 15 and the outer wall of the basket 13. It is to be understood that the under side of the member 15 is left entirely open.

In applying the structure to the chimney or flue 10, the basket 13 is brought up against the flue to have its lower edge positioned horizontally across but somewhat below the lower edge of the opening into the flue, the basket being preferably lowered to have the lower edge of the flap 14 approximately in the same elevation as that of the lower edge of the flue opening. The upper member 15 is adjusted vertically and horizontally to be brought up against the bricks 11 and 12 to have the inner edges of the flanges about the member abut the bricks 11 and 12. The bolts 16 and 17 are inserted to align to member 15 and retain it snugly against the bricks as above outlined. The vertically disposed flanges on the sides of the member 15 are preferably cut back somewhat, Fig. 1, so as to permit the sloping flanges to be advanced beyond the vertical edge of the basket 13, as indicated by the solid lines

in Fig. 4, should the bricks 11 be back from the vertical side of the flue. Should the bricks 11 extend outwardly beyond the side of the flue, then the upper member 15 may be adjusted back to some such position as indicated by the dash lines in Fig. 4. Also the two members may be adjusted vertically in relation to each other to conform and cover over openings having varying heights. The basket 13 and upper member 15 are made to overlap the bricks around the flue opening an appreciable extent, sufficient in any event to take care of any variation in size of the opening in the horizontal direction. Both openings from the flue 10 are covered in the manner as above described and the two screens are fixed in position by any suitable means, here shown as by the wires 18 and 19 passing around the sides of the flue to pull the two units thereagainst.

The draft within the flue will generally carry particles of soot and the like out through the side openings in the general direction of the arrow as indicated in Fig. 1, whereby the particles first are caught and retarded by the upper member 15, wherein the impact of the particles thereagainst will tend to break them up and allow the smaller ones to escape while the larger particles will continue on downwardly around the under side of the member 15 to be well down to within the basket 13 to either strike the bottom thereof or be whirled around under the influence of the draft escaping from the flue against the outer wall of the basket to become further broken-up. In the event that the perforations through the basket and the member 15 become filled in, then the normal draft of the flue will not be interfered with since the gases may escape from under the member 15 and up from the top of the basket 13, with the auxiliary opening under the flap 14. Winds blowing across the flue and the screens thereon, may at times enter through the openings under the flap 14 to aid materially in keeping the baskets clean.

While I have herein described my invention in one particular form, it is obvious that structural changes may be made without departing from the spirit of the invention and I, therefore, do not desire to be limited to that precise form beyond the limitations as may be imposed by the following claims.

I claim:

1. In a spark screen for a flue side-outlet, a perforate basket open at the top and inner side, and an upper member telescoping with the basket and having in-turned flanges less in width than that of the basket, a wall extending from the outer side of the member well down within the basket to form a partition thereacross with an opening thereunder.
2. In a spark screen for a flue side-outlet, a perforate basket open at the top and inner

- side, and an upper member telescoping with the basket and having inturned flanges less in width than that of the basket, a wall extending from the outer side of the member 5 well down within the basket to form a partition thereacross with an opening thereunder, and means adjustably retaining the member in selected positions in relation to the basket.
3. In a spark screen for a flue side-outlet, 10 a perforate basket open at the top and inner side, and an upper member telescoping with the basket and having inturned flanges less in width than that of the basket, a wall extending from the outer side of the member 15 well down within the basket to form a partition thereacross with an opening thereunder, said basket having a horizontal opening across its outer wall and a flap inturned above the opening.
- 20 4. In a spark screen for a side outlet opening, a lower screen adapted to fit about a part of the flue opening, and an upper screen adapted to fit about the remainder of the opening, one of said screens being less in 25 width than the other, and means adjustably uniting the two screens, said screens being positioned to afford a tortuous passage across one screen, thereunder, and back across the other screen.
- 30 5. In a spark screen for a side outlet opening, a lower screen adapted to fit about a part of the flue opening, and an upper screen adapted to fit about the remainder of the opening, one of said screens being less in 35 width than the other, and means adjustably uniting the two screens, said screens being positioned to afford a tortuous passage across one screen, thereunder, and back across the other screen, said lower screen having a horizontal opening thereacross near its under 40 side, and a deflecting flap over said opening.
6. In a spark screen for a side outlet opening, a lower screen adapted to fit about a part of the opening, an upper screen adapted to 45 fit about the remainder of said opening, said screens telescoping one with the other, said upper screen having a transverse wall extending down within said lower screen as a baffle, and means adjustably securing the 50 screens together.
7. In a spark screen for a side outlet opening, a lower screen adapted to fit about a part of the opening, an upper screen adapted to fit about the remainder of said opening, said screens telescoping one with the other, said upper screen having a transverse wall extending down within said lower screen as a baffle, and means adjustably securing the screens together, said upper 55 screen having in-turned flanges, and said wall having similar in-turned flanges but less in width.
8. In a spark screen for a side outlet opening, a lower screen adapted to fit about a part of the opening, an upper screen adapted 60 65
- to fit about the remainder of said opening, said screens telescoping one with the other, said upper screen having a transverse wall extending down within said lower screen as a baffle, and means adjustably securing the 70 screens together, said upper screen having in-turned flanges, and said wall having similar in-turned flanges but less in width, said upper screen being less in width than that of the lower screen.
- 75
- In testimony whereof I affix my signature.
